GRINDING MACHINE

Julius V. Bergfeldt, New Britain, Conn.

Application July 27, 1938, Serial No. 221,499

4 Claims. (Cl. 51—134)

The present invention relates to grinding machines and more particularly to a grinder having a plurality of work holding chucks rotatably carried past one or more grinding wheels.

5 The object of the present invention is an improved machine of the above-indicated type wherein there is provided a rotating work table having a plurality of work holding chucks thereon and one or more grinding wheels located above 10 the work table and adapted to surface grind the work carried in the chucks.

A still further object is a grinding machine having improved means for maintaining the grinding surfaces of the wheels sized and dressed 15 without interruption in the operation of the machine.

A still further object is a machine having improved means for feeding the grinding wheels toward the work and including means for controlling such feed in timed relationship to the rotation of the feed table.

A still further object is a machine wherein the speed of the grinding wheels may be varied and including improved variable driving means.

25 Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a front view of a machine embodying the invention herein;

Fig. 2 is a plan view of Fig. 1;

Fig. 3 is a detail view of the manual and automatic means for feeding the grinding wheel shafts;

40 Fig. 4 is a sectional view on the line 4—4 of Fig. 3;

Fig. 5 is a view partially in section of the variable driving means;

Fig. 6 is a sectional view of the variable drive 45 pulley assembly;

Fig. 7 is a fragmentary sectional view of a grinding wheel shaft and the feeding spindle therefor; and

Fig. 8 is a detail view of the variable drive 50 supporting bracket.

Referring to the drawings, the machine includes a cylindrical supporting base 10 in which there is centrally located a shaft 12 on which is mounted a rotatable work holding table 14, the 55 diameter of which is somewhat less than the di-

ameter of the supporting base 10. Intermediate of the periphery 15 of the work supporting table 14 and the periphery 11 of the base 10, the base is provided with a horizontally arranged outer top plate 16 and an inner top plate 18; the 5 inner top plate being spaced below the outer plate 16 by a vertically arranged shoulder 20. The work holding table 14 is adapted to be rotated about the shaft 12 by any suitable variable drive mechanism which may be located in the 10 base 10, which drive mechanism has been omitted for purpose of simplicity.

The work table carries a plurality of work holding chucks 22 which have been shown more or less diagrammatically and are provided with 15 suitable jaws adapted to be closed for a portion of rotation of the table and opened during the remainder of the rotation to allow the work pieces to be readily removed therefrom and new work pieces placed therein. The jaws of each 20 chuck are automatically opened and closed by a plunger 24 provided on its outer end with a roller or follower 26 which is spring pressed into engagement with the vertical surface of the shoulder 20 during the angle of rotation in which the 25 jaws are open and adapted to receive the work pieces. The follower is adapted to ride over a cam 28 arranged on the shoulder 20 for urging the plunger inwardly to close the jaws 30 during the angle of rotation in which the work pieces must be securely held.

The work pieces are thus rotated beneath suitable grinding wheels 30 which are vertically carried on a support 32 which extends upwardly from the top plate 16 and carries a substantially 35 triangular shaped housing 34, which housing overhangs the inner top plate 18 of the base 10 and the work holding chucks of the rotatable table 14, with the apex of the housing being closest to the center shaft 12, as viewed in Fig. 40 2. The sides 36 and 38 of the housing are arranged at right angles to one another, and each side makes an angle of 135° with a diameter extending through the center of the shaft 12 and the apex of the housing.

45 The housing provides a duplex support for the grinding wheels 30 and their associated driving mechanism, and inasmuch as the construction of each is identical, only one will be described, with like numbers applied to the other. As best 50 seen from Figs. 4 and 5, there is mounted on each side wall 36, by suitable bolts 40, a vertically arranged base plate 42. The upper portion of the base plate 42 has secured thereon an upper spindle housing 44 and shaft housing 46. The 55

lower portion of the base plate 42 has bolted thereon suitable ways 48 in which there are slidably mounted a lower spindle housing 50 and shaft housing 52. The upper and lower shaft 5 housing 46 and 52 are provided with aligned bores for receiving a grinding wheel shaft which is provided on its lower end with a grinding wheel supporting plate 56 on which the grinding wheel 30 may be secured in any suitable way.

10 The portion of the shaft 54 which is positioned in the lower shaft housing 52 is provided with upper and lower threaded portions 58 (the upper end being shown in Fig. 7); the threaded portions being adapted to receive a securing nut 60

15 adapted to position therebetween suitable upper and lower ball bearing races 62 and a spacing sleeve 64. Positioned between the nut 60 and the top plate of the housing 52 there may be provided any suitable spacer 66 to cause simultaneous vertical movement of the housing 52 and the shaft 54 for raising and lowering the drive shaft and grinding wheel, as hereinafter explained. The drive shaft 54 extends above the housing 52 and into a sleeve 68 rotatably mounted in the upper shaft housing 46; the shaft being suitably keyed in the sleeve to permit vertical movement relative thereto. The upper end of the sleeve 68 extends above the housing 46 and has secured thereon a drive pulley 70 having a top and bottom groove therein. The pulley 70 connects through suitable driving belts 72 and 74 to a pair of pulleys 76 and 78 arranged on the upper end of an intermediate driving member 80; the lower end thereof carrying a pair of pulleys 82 and 84, which in turn connect through suitable belts 86 and 88 to a pulley 90 mounted for rotation on a shaft 92 of a drive motor 94.

As may best be seen in Fig. 2, the motor 94 is mounted on a wall 96 extending at right angles to the wall 36 of the housing 34, and the intermediate driving member 80 is adjustably mounted on a bracket 98, which bracket is secured to a wall 100 positioned within the housing 34. The intermediate driving member 80 may be adjusted 45 to vary the speed of the grinding wheel 30, and to accomplish this the member 80 comprises a center shaft 102 rotatably supported in a bracket 104, which bracket is provided with a shoe 106 mounted for slideable movement in the ways 108 of the supporting bracket 98. The ways 108 are arranged at an angle of 15° to the horizontal, whereupon movement of the bracket 104 will move the shaft 102 transversely of the wall 100. In order to transmit the angular movement of the member 102, the various driving pulleys and driving belts heretofore mentioned are provided with cooperating grooves and drive surfaces, all of which taper at an angle of 15° to the horizontal.

The upper and lower sets of pulleys on the shaft 102 each comprises independent cooperating members adapted to be moved toward and away from one another and are so arranged that upon transverse movement of the shaft 102 the upper and lower pulleys will open out or close in in opposed relationship to one another (see Fig. 6). To accomplish this, the upper member 110 of the pulley 76 is spaced from the upper member 112 of the pulley 78 by a sleeve 114; the pulley members 110 and 112 being mounted on a reduced portion 116 of the shaft 102, with the pulley member 112 abutting against the upwardly facing shoulder 118 intermediate of the enlarged and reduced portions of the shaft 102. The lower member 120 of the pulley 76 is mounted on the

outer surface of the sleeve 114 and connects through suitable bolts 122 which extend through the member 112 to the lower member 124 of the pulley 78; the member 124 being mounted on the outer surface of a sleeve 126 which is rotatably mounted in the bracket 104 and in which the shaft 102 may be moved vertically.

The lower set of pulleys 82 and 84 are similarly constructed and corresponding parts have been correspondingly numbered, with the suffix "a" added thereto. With this arrangement, the pulley members 124 and 124a are spaced apart at a fixed distance by the sleeve 126 and the interposed ball bearing races 128, and upon adjustment of the bracket 104 the members 124 and 124a will be moved transversely and simultaneously raised or lowered, depending upon the direction of movement of the bracket. Thus if the bracket 104 is moved to the left, as viewed in Fig. 6, the members 124 and 124a will be raised and will simultaneously cause the members 120 and 120a, which are connected thereto, to be raised. As the tapered surfaces of these members ride over the tapered surfaces of the connecting belts, the shaft 102 will be drawn downwardly, thus causing the members of the upper set of pulleys 76 and 78 to close in and the members of the lower sets of pulleys to open out, thus changing the position of the belts on the driving surfaces and varying the speed from the motor 94 to the pulley 70.

The bracket 104 may be adjusted to adjust the variable stepless pulleys by a suitable threaded stem 130 which extends into a threaded opening therein and projects outwardly therefrom and through a sleeve 132 in the rear wall 134 of the housing 34; the stem being prevented from longitudinal movement in the sleeve by a suitable collar 136 and the manually operable handle 138. Thus it will be seen that the speed variation of the grinding wheel has an infinite range which not only permits the variation of the speed of any one grinding wheel, but allows the use of various sizes of grinding wheels on the same drive shaft.

There is also provided means for lowering and raising the grinding wheel towards and from the work holding pieces, and to accomplish this there is mounted in the upper spindle housing 44 the reduced upper end of a spindle 140 (see Fig. 7) which extends through a suitable bore 142 and is secured in place by a nut 144 and held against rotation by a key 146. The spindle extends down and through an aligned bore in the lower spindle housing 50, which housing has rotatably mounted therein a sleeve 148 correspondingly threaded to 55 and adapted to be rotated on the spindle 140.

The lower end of the sleeve 148 terminates in a bevel gear 150 which cooperates with a bevel gear 152 secured on the inner end of a control shaft 154 (see Fig. 4), which shaft extends through and out of the shaft housing 52 and has secured on its outer end a suitable manually operable control wheel 156. Upon rotation of the wheel 156, the shaft 154 will rotate gear 152 to cause rotation of the bevel gear 150 and the sleeve 148, whereupon the sleeve 148 will move vertically on the spindle 140 to move the shaft housing 52 and grinding wheel shaft 54 up or down, depending upon the rotation of the control wheel, and thus adjust the grinding wheel relative to the work pieces.

As it is desirable to automatically lower the grinding wheel 30 towards the work pieces, there is positioned intermediate of the shaft housing 52

and the manual control wheel 156 a ratchet wheel 158 which is secured in any suitable way to a sleeve 160 splined onto the shaft 154 for simultaneous rotation therewith. The wheel 158 is enclosed in a housing 162 having mounted therein a ratchet dog 164 which is normally spring pressed into engagement with the ratchet wheel 158 and may be cammed out of engagement therewith by a manually operable lever 166 when it is desired 10 to manually operate the shaft 154 and raise or lower the housing.

The housing 162 is mounted for rotation about the shaft 154 and sleeve 160 and is provided with a rearwardly extending link 168 which connects 15 to the depending lever 170 of a solenoid 172. The weight of the solenoid and the connecting linkage 168 and 170 is such as to normally rotate the housing 162 in a clockwise direction, as viewed in Fig. 3, to position the ratchet dog 164 under 20 one of the teeth of the ratchet wheel 158. The housing 162 is also provided with a laterally extending arm 174 and an inwardly projecting lug 176 adapted to abut the top and bottom adjustable stops 178 and 180. The stops 178 and 180 are 25 carried on spaced apart ears 181 extending from member 182 positioned intermediate of housing 162 and a solenoid casing supporting plate 184; the members 182 and 184 being secured to the shaft housing 52 by a suitable bolt 186. The stops 30 178 and 180 may be adjusted to limit the angular movement of the housing 162 and thus vary the number of teeth over which the ratchet dog 164 rides and control the amount of feed of the grinding wheel.

The solenoid 172 is normally de-energized (see 35 Fig. 3) and becomes energized upon the closing of a suitable switch mounted on the outer plate 16 of the base 10 (see Fig. 2) which switch 188 is periodically actuated by a cam member 190 carried on a supporting plate 192 secured to the 40 rotatable work holding table 14. Upon closure of the switch 188, the solenoid 172 will become energized (through suitable connections not shown) to rotate the housing 162 in a counter-clockwise direction, whereupon the dog 164 will 45 rotate the ratchet wheel 158 to rotate shaft 154 and lower the grinding wheel 30 a predetermined amount, depending upon the setting of stops 178 and 180. Upon the automatic opening of switch 50 188, the solenoid will become de-energized, and the weight of the associated linkage as heretofore described will rotate the housing clockwise to position the dog 164 for the next lowering operation.

Another improvement in the present grinding machine is the provision of means for sizing and dressing the grinding wheels 30 at predetermined 55 times during the revolution of the table 14. In the embodiment illustrated, the wheels are adapted to be sized and dressed once during each revolution, and to accomplish this there is provided a pair of spaced apart diamonds 194 and 196 vertically arranged on the supporting plate 192. As 60 may be seen from Fig. 2, the grinding wheels are not symmetrically disposed with reference to the center of the work rotating table. Considering the table to be rotating in a counterclockwise direction, the first wheel to be reached by the diamond is adapted to rough grind the work and 65 is offset from the center of the table by a distance A; whereas the second wheel, which is adapted to finish grind the work, is offset from the center a lesser distance B. The diamond 194 is so positioned that upon rotation of the table it will pass

beneath the roughing wheel and will engage same intermediate of the center and the outer periphery thereof, and thus in sizing and dressing of the wheel it will do so without hollowing out or giving the wheel a concave surface.

The diamond 196 is so spaced from the diamond 194 that it will pass inwardly of the roughing wheel. However, upon further rotation of the table, the diamond 196 will engage the finishing wheel intermediate of the center and the inside periphery thereof; whereas the diamond 194 will clear the finishing wheel. It will be noted that the supporting plate 192 is positioned just ahead of the first open chuck into which a new piece of work has been placed. Upon rotation of the 15 table, the cam 190 will cause the grinding wheel to be lowered immediately after the last piece of work has been ground by the wheel and immediately before the sizing and dressing diamond 194 contacts the wheel. Thus when the wheel 20 engages the next piece of work, it will be properly sized and dressed to rough grind the work a predetermined amount. Upon further rotation, the cam 190 will engage the second switch 188 to lower the finish grinding wheel into position to be operated 25 upon by the finishing diamond 196.

It is apparent that if the type of work is such that more than one sizing and dressing of the wheels is required, a plurality of supporting plates and diamonds could be positioned around the periphery of the rotating table 14. As it is sometimes desirable to arrange the lower surface of the grinding wheels off the horizontal, the base plate 42 (see Fig. 5) is provided with an adjustment stud 198, which stud may be 30 screwed in against the wall surface 36 to tilt the supporting plate 42. Inasmuch as the amount of tilt in grinding work is only a matter of thousandths, the required amount may be accomplished without disturbing the securing hold of 35 the bolts 40.

From the foregoing, the operation of the machine appears obvious; it being apparent that once the machine is placed in operation and properly adjusted for the particular type of 45 work to be ground the entire operation thereafter will be automatic.

As many changes could be made in the above construction and many apparently widely different embodiments of this invention could be made 50 without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of 60 language, might be said to fall therebetween.

I claim as my invention:

1. In a machine of the character described, a rotatable work holding table, a pair of grinding wheels supported above said table, each of said 65 grinding wheels having a flat radial grinding surface facing the work holding table, a pair of sizing and dressing means carried by said table, one of said means being adapted to size and dress the radial surface of one of said wheels and 70 clear the other, and the other of said means being adapted to clear said first wheel and size and dress the radial surface of said other wheel as the work holding table rotates.

2. In a machine of the character described, a 75

5 rotatable work holding table, a pair of grinding wheels supported above said table, each of said grinding wheels having a flat radial grinding surface facing the work holding table, one of said grinding wheels being at a greater radius from the center than the other, a pair of sizing and dressing means carried by said table, one of said sizing and dressing means being at a greater radius from the center than the other and adapted to size and dress the radial surface of the 10 grinding wheel at the greater distance from the center and clear the wheel at lesser distance, said other sizing and dressing means being adapted to size and dress the radial surface of 15 the other grinding wheel and clear the wheel at greater distance.

3. In a machine of the character described, a rotatable work holding table, a grinding wheel positioned above said table, ratchet means

for feeding said grinding wheel towards said table, a solenoid adapted to actuate said ratchet means, and a switch adapted upon being closed to energize said solenoid, and means carried by said table for periodically closing said switch. 5

4. In a machine of the character described, a rotatable work holding table, a plurality of work holding chucks carried by said table, sizing and dressing means carried by said table intermediate of a pair of said work holding chucks, a 10 grinding wheel supported above said table, means for feeding said grinding wheel toward said table, and means carried by said table intermediate of a work holding chuck and said sizing and dressing means for actuating said grinding wheel 15 feeding means, whereby said wheel will be sized and dressed intermediate of the passage of two of said work holding chucks.

JULIUS V. BERGFELDT.
